UNITED STATES PATENT OFFICE

GOTTFRIED BIERMANN, OF BERLIN-CHARLOTTENBURG, AND CARL NIEMANN, OF BERLIN, GERMANY, ASSIGNORS TO SIEMENS & HALSKE, AKTIENGESELLSCHAFT, OF SIEMENSSTADT, NEAR BERLIN, GERMANY, A CORPORATION OF GERMANY

X-RAY DEVICE

Application filed March 13, 1926, Serial No. 94,578, and in Germany March 14, 1925.

The present invention relates to improvements in X-ray devices.

In X-ray devices for therapeutic uses several conditions must be satisfied on account of the high electrical tensions which are employed. It is however very difficult to satisfy all these conditions simultaneously.

On one side a sufficient protection must be provided against accidental contact of persons with parts of the apparatus carrying high voltages and against the evolution of noxious gases, as well as against the spreading of the X-rays beyond the area where their action is desired. On the other hand the device must nevertheless be easily handleable and so arranged that the effective beam of rays which is screened off for the treatment can be thrown in any direction in which it is to be used.

20 The usual X-ray devices do not satisfy these conditions simultaneously.

In X-ray tubes operating with very high tensions the electrode-carrying tubular ends are in themselves very long. It has been proposed to enclose such tubes in a tube-shaped container. This expedient gives a sufficient protection against stray rays but makes the device very unhandy. Such devices were movably arranged. The input 30 wires for the electrodes were passed through the side wall of the container, so that the high tension wires lay unprotected. This is very disturbing, especially when the device is moved in order to throw the rays in a certain 35 direction, because the wires in such cases are shifted continually.

To avoid these drawbacks, constructions were devised in which the tubes and the conducting wires were enclosed in large metallic 40 containers, usually grounded and secured to a wall. Arrangements of this kind have the advantage that the partition or wall separates the chamber or compartment containing the high tension apparatus from the chamber containing the patient to be treated with X-rays. Also, all conductors carrying high tension currents are enclosed in the container and carried through the wall into the high tension chamber, so that injurious gases 45 can be conveyed away readily. However,

these devices also are unhandy, since on account of the rigid fastening of the container to the wall it becomes necessary to place the patient on a table adapted to be placed in different positions and provided with means 55 for its vertical adjustment.

These drawbacks are avoided by our present invention. We employ a readily adjustable high-tension-proof and X-ray-proof tubular container for the X-ray tube, and 60 make provision for preventing the passage of gases into the treatment chamber. The container is adapted to be raised or lowered, preferably transversely to its longitudinal axis, and extends through the partition 65 separating the treatment chamber from the high tension chamber. The container is adapted to be turned about its longitudinal axis, and the X-ray tube is preferably arranged co-axially within the container, so 70 that the beam of X-rays may be thrown in any direction perpendicular to the said axis of the container and of the tube. The container may be connected to the raising and lowering mechanism at both ends, or at a 75 point between the ends of the container, preferably about midway between them. In this latter case, only one point of the container is connected with the raising and lowering mechanism, and a horizontal pivot or like connection may be arranged at this point. 80

Two examples of our invention are illustrated by the accompanying drawings, in which Fig. 1 is a front elevation of one embodiment of our X-ray apparatus, with parts 85 in section; Fig. 2 is a side elevation thereof, with parts in section; Fig. 3 is a plan view, likewise with parts in section; and Figs. 4, 5, and 6 are corresponding views showing another form of our invention. 90

As represented in Figs. 1, 2, and 3, the container 1 for the X-ray tube 2 is a hollow cylinder made of hard paper. An external coating or sleeve 3 of lead is applied to that part of the container which surrounds the X-ray 95 tube. Sockets 4 made of lead glass are secured to the extremities of the X-ray tube. The container 1 is mounted to turn about its longitudinal axis, so that a beam of X-rays, which passes out through the window or 100

screen 5, may be projected in different directions in a plane perpendicular to said axis. The supporting brackets or carriers 6, 7 in which the container 1 is thus mounted to turn, 5 can be raised or lowered in unison by means of wires 9 engaging suitable guide rolls and equipped with counterweights 8. The carrier 6 and the adjacent wall along which it is movable, separate the treatment chamber 10 I from the chamber II in which the high tension generator (not shown) is located; the other carrier 7 moves along, and virtually forms a part of, one of the walls of a box-like closet III, situated within the treatment 15 chamber I. 10 designates a high tension wire or terminal extending axially from one end of the tube 2 through the container 1 into the high tension chamber II, the other terminal extending in the opposite direction from 20 the other end of the tube 2 into the closet III. Through the ceiling of this closet, such other terminal is passed as a telescopic tube 11, and is then extended under the ceiling of the treatment chamber I into the high tension 25 chamber II. Accidental contact of the operator or patient with the high tension conductors is thus absolutely prevented. Another advantage of this construction is that the conductors are arranged in fixed positions and 30 thus may be given such ample dimensions that the formation of noxious gases is avoided.

The high tension conductor 12, which is 35 laid along the ceiling, is preferably made tubular, to serve as a conduit for compressed air. This air is blown through the tubular conductors 12, 11 into the container 1, to pass along the X-ray tube 2 and is then discharged into the high tension chamber II, as indicated 40 in Fig. 2. An efficient cooling of the tube is thus obtained, and any gases that may be formed, are driven into the high tension chamber II through the end of the container 1 which opens into said chamber.

45 The table 13 upon which the patient is laid is preferably arranged lengthwise under the container 1. In some cases, it may be necessary to place the table crosswise under the container 1, because the inclination of the 50 beam can be varied in one plane only. This latter objection is overcome by the form of our invention illustrated by Figs. 4, 5, and 6.

In this form, one of the high tension terminals of the X-ray tube 2, arranged axially in 55 the hard paper cylindrical container 1, passes out of the container axially, preferably not as a wire of relatively small diameter, but as a tube 15 lining the inner wall of the container 1. The other high tension terminal is 60 laid in the same direction on the outside of the container 1. In order to prevent rupture or perforation by so-called point discharges, this terminal is formed as a tube 16 which 65 surrounds the outer wall of the tubular container 1 closely. By the electrostatic effect

of said tube 16 cylindrically surrounding the X-ray tube 2, the operation of the latter is improved very much, the discharges being very uniform and quiet. In order to insulate this terminal, a second hard paper cylinder 17 is arranged on the outside of the container 1. Around this cylinder 17 is laid the lead jacket 3.

Instead of adopting the arrangement just described, a grounded lead tube may be substituted for the other terminal 16. If the positive pole of the source of high tension current is grounded, the return conductor and the lead jacket 3 will be dispensed with, and the container for the X-ray tube then 70 becomes a one-pole device.

The container with the X-ray tube therein and associated parts can be rotated or turned about its longitudinal axis in a ring-shaped socket or carrier 18, so that the beam of X-rays can be emitted in any direction. To facilitate such turning of the container, the latter may be provided with handles 24. The socket 18 is arranged at the central portion of the container, so as to secure a partial balancing thereof, and it will be noted that one end of said container is in the high tension chamber II, while the other end is located in treatment chamber I. The socket 18 is connected with a fork 20 by means of horizontal 85 trunnions 19. In order that the source of the X-rays may be adjusted to different levels, the fork 20 may be raised or lowered on rails 21 by means of two wires 9, engaging suitable 90 guide rolls and equipped with counterweights 8. A cover plate, 22 connected with the fork 20, closes the opening in the wall and separates the treatment chamber I from the high tension chamber II, although a 95 communication between said chambers is afforded by openings in the tube-shaped device.

The cylinder 17 may be closed by a perforated plate 23 or by a screen.

By arranging a suction fan 25 in the high tension chamber II, a current of air may be caused to flow from the treatment chamber I through the container 1 and along the X-ray tube 2 into the high tension chamber II. Thus the said tube is cooled and any noxious gases which may be formed, are sucked into the high tension chamber without having any opportunity to reach the treatment chamber.

Various modifications may be made without departing from the nature of our invention as set forth in the appended claims.

We claim:

1. In an X-ray device, a chamber adapted to contain apparatus for the production of high tension electric energy for the production of X-rays, another chamber adapted to contain the patient, a wall separating said chambers, a carrier movable up and down adjacent to said wall, an insulated tubular container supported on said carrier and 125

journalized therein to turn about the longitudinal axis of the container, and an X-ray tube surrounded by said container and movable therewith.

5. 2. In an X-ray device, a chamber adapted to contain apparatus to supply high tension current for X-ray production, another chamber for the reception of the patient, a wall separating said chambers and provided with 10 an aperture, a container extending through said aperture and movable up and down therein, an X-ray tube within said container, and a cover for closing said aperture.

3. In an X-ray device, a chamber adapted 15 to contain apparatus to supply high tension current for X-ray production, another chamber for the reception of the patient, a wall separating said chambers, a carrier movable up and down adjacent to said wall, a container 20 extending from one of said chambers into the other, the middle portion of said container being supported on said carrier movably to allow the container to turn about its longitudinal axis, and an X-ray tube 25 mounted within said container.

4. In an X-ray device, an X-ray tube, a cylindrical container for said tube, and conductors of cylindrical shape, mounted on the inside and on the outside respectively of said 30 container, for carrying current to said tube.

5. In an X-ray device, a chamber adapted 35 to contain apparatus to supply high tension current for X-ray production, another chamber for the reception of the patient, a wall separating said chambers, a carrier movable up and down adjacent to said wall, a cylindrical container the central portion of which is supported by said carrier movably to allow the container to turn about its longitudinal 40 axis, the ends of said container being in said first-mentioned and in said second-mentioned chamber respectively, conductors of cylindrical shape, mounted on the inside and on the outside respectively of said container, 45 and an X-ray tube located within said container and adapted to receive current from said conductors.

6. In an X-ray device, an X-ray tube, a cylindrical container for said tube, a cylindrical conductor mounted on the inside of 50 said container, and another cylindrical conductor mounted around the outside of said container and surrounding the X-ray tube.

7. In an X-ray device, an X-ray tube, a 55 cylindrical container for said tube, cylindrical conductors for supplying current to said tube, mounted on the inside and on the outside respectively of said container, an insulating layer covering the outer conductor, and a metallic cover surrounding said 60 layer and adapted to be grounded.

8. In an X-ray device, an X-ray tube, a 65 tubular container enclosing said tube, a carrier socket in which said container is mounted to turn about the axis of the container, and

a supporting member movable transversely to said axis and connected with said socket pivotally about an axis transverse both to the axis of the container and to the path of movement of said supporting member.

In testimony whereof we affix our signatures.

GOTTFRIED BIERMANN.
CARL NIEMANN.
